(57) **CLAIM**

The ornamental design for a LED energy-saving lamp, as shown and described.

DESCRIPTION

FIG. 1 is a top perspective view of a LED energy-saving lamp showing our new design;

FIG. 2 is a front elevation view of the LED energy-saving lamp of FIG. 1 thereof;

FIG. 3 is a top view of the LED energy-saving lamp of FIG. 1 thereof;

FIG. 4 is a bottom view of the LED energy-saving lamp of FIG. 1 thereof;

FIG. 5 is a right side view of the LED energy-saving lamp of FIG. 1 thereof; and,

FIG. 6 is a left side view of the LED energy-saving lamp of FIG. 1 thereof.
